COFFEE MAKER

William P. Biehayn, Richmond Hill, N. Y., assignor to S. W. Farber, Inc., New York, N. Y., a corporation of New York

Application March 1, 1950, Serial No. 8,227

Term of patent 14 years

(Cl. D44—26)

To all whom it may concern:

Be it known that I, William P. Biehayn, a citizen of the United States, residing at Richmond Hill, county of Queens, State of New York, have invented a new, original, and ornamental Design for a Coffee Maker, of which the following is a specification, reference being had to the accompanying drawing, forming a part thereof.

The dominant features reside in the parts shown in full lines.

I claim:

The ornamental design for a coffee maker, as shown.

WILLIAM P. BIEHAYN.
